Harry E. Strunk,
by *Myron L. S. Hunt*,
His Attorney.

UNITED STATES PATENT OFFICE.

HARRY E. STRUNK, OF ONTARIO, CALIFORNIA, ASSIGNOR TO EDISON ELECTRIC APPLIANCE COMPANY, INC., OF CHICAGO, ILLINOIS, A CORPORATION OF NEW YORK.

ELECTRIC HEATER.

Application filed January 16, 1924, Serial No. 686,623. Renewed November 8, 1927.

My invention relates to electric heaters, particularly to means for protecting electric heaters from over heating, and has for its object the provision of improved means of this character.

My invention has particular application to electric flatirons, although obviously it has various other applications.

More specifically, my invention relates to protective devices in which a fusible metal or alloy is employed for securing a switch holding member which is released upon the fusing of the alloy whereby the heating circuit is opened. As sometimes used, the fusible alloy is held in a suitable container into which the switch holding member extends so as to be embedded and secured in the alloy. Such arrangements have the disadvantage, however, that the switch holding member may be loosened due to shrinkage of the alloy in cooling. Also there is a tendency for the switch holding member to creep in the alloy.

In carrying out my invention, I provide suitable anchoring means for the switch holding member whereby looseness and creeping are prevented.

For more complete understanding of my invention, reference should be had to the accompanying drawing in which Fig. 1 is an elevation view partially in section of an electric flatiron embodying my invention. Fig. 2 is an enlarged plan view of the switching mechanism showing the switch in closed position. Fig. 3 is an enlarged view in section showing the anchoring means for the switch holding member, while Fig. 4 is a sectional view of the line 4—4 of Fig. 3 looking in the direction of the arrows.

Referring to the drawing, I have shown my invention in one form as applied to a well known type of flatiron comprising a sole plate 10 and a pressure plate 11 between which is clamped a suitable electric heating unit 12. As shown, the plates are secured together by means of a screw 13. In the sole plate is a circular recess 14 in which is secured a sealed receptacle 15 containing a fusible metal or alloy 16. The receptacle 15 is made of suitable material such as steel

and has its surface oxidized or otherwise treated or protected to prevent amalgamation at high temperature with the fusible metal, for example when the fusible metal is in a molten condition. Extending upward from the receptacle 15 through an opening 17 in the pressure plate is a stem or switch holding member 18 having a portion 19 of reduced size at its upper end, which portion extends through a suitable aperture in a lever member 20 cooperating with the switching mechanism for the circuit of the heating unit 12. The lower end of the stem 18 extends into the receptacle 15 and is embedded in the fusible metal. The stem 18 is thus normally secured in an upright position and when so secured is adapted to hold the switching mechanism in closed circuit position. Upon the occurrence of an excessive temperature resulting in fusing of the alloy metal, the stem is freed and can tilt to one side to permit the opening of the heating circuit.

Any suitable switching mechanism may be used in the circuit of the heating unit 12. The particular switching mechanism shown is described and claimed in United States Patent #1,439,979 to Earl H. Richardson, dated December 26, 1922, and therefore will not be described in detail. The member 20 is pivotally mounted at its center on a supporting plate 21, which is secured on the top of the pressure plate 11, and is constrained to rotate about its pivot in a clockwise direction as viewed in Fig. 2 by means of a helical reset spring 22 having one end secured to member 20 and its other end secured to plate 21. In the position shown in Fig. 2, the member 20 stands in its extreme position in a clockwise direction such that it is brought to rest by the engagement of the stem 18 with a projection 23 on support 21. The member 20 is held against rotation in a counter-clockwise direction from this position by means of the stem 18, which in turn is secured by the fusible metal, and thus holds the switching mechanism in closed circuit position against the force exerted by a comparatively strong spiral spring 24. This spring has one end 25 secured to supporting plate 21 while its other end is operatively

connected through a link 26, yoke 27, and link 28 to the movable end of a switch arm 29 the other end of which is pivoted on suitable knife edge bearings 30. The yoke member 27 is held on one end of a Z shaped latching member 31, the opposite end of which co-operates with a projection 32 on the left-hand end of member 20. The latching member 31 is provided with knife edge 10 bearings 33, which rest on the end of an operating arm 34 the other end of which is provided with knife edge bearings 35 on which the member is pivoted. The action of the spring 24 is in such direction as to tend 15 to throw the switch arm 29 in a counter-clockwise direction about its pivot and thus move the bridging circuit closing member 36 away from the stationary contacts 37 and 38 to open the heating circuit. As long as the 20 member 20 is held by the fusible metal in the position shown in Fig. 2, the switch is maintained closed by the engagement of latch 31 with the projection 32. In case of excessive temperatures, however, sufficient 25 to fuse the metal 16, the stem 18 will be released allowing member 20 to rotate in a counter-clockwise direction under the influence of the force applied by spring 24 until latch 31 slips off projection 32 whereupon 30 the switch will be opened. Member 20 is immediately thereafter returned to the position shown in Fig. 2 by the reset-spring 22 so that after the stem 18 has been again secured by the solidification of the fusible 35 metal, the heating circuit may be closed by pressing inward on the button 39 which is attached to the operating member 34.

As shown in Figs. 3 and 4, the receptacle 15 for the fusible metal is provided with a 40 cover 40 which is a flexible diaphragm made of a suitable metal such as manganese nickel. The receptacle 15 has a flanged top upon which the cover or diaphragm 40 rests, a clamping ring 41 being placed on the diaphragm and the container sealed by means 45 of a brazed or welded joint 42 between the flanged edge of the receptacle, the diaphragm and the clamping ring. The stem 18 is carried by the diaphragm 40 and extends centrally through it into the fusible 50 metal 16. It is tightly secured to the diaphragm in this central position by means of a brazed or welded joint 43. It will be observed that the receptacle 15 is thus sealed 55 so that the fusible metal 16 is protected against oxidization. When the metal fuses releasing the lower end of the stem, the diaphragm flexes so as to permit the stem to tilt and in effect acts as a pivot for the stem.

60 In accordance with my invention, I provide special anchoring means for the lower end of the stem 18. In one form of my invention, I provide an inverted U-shaped metallic anchoring member 44 provided with 65 slots so as to form a plurality of down-

wardly extending projections 45 and 46 on the sides, four being shown on each side. These projections extend into the fusible metal. The anchoring member 44 straddles a transversely extending fixed anchor member 70 47 which is secured to the receptacle 15, for example, by providing recesses or notches 48 and 49 in its ends and pressing the wall of the receptacle 15 into these notches. In the member 47 is a plurality of 75 apertures 50, three being shown. A recess 51 is provided in the sole plate 10 with which an emboss on the receptacle 15 is adapted to register and secure the receptacle 80 in a fixed angular relation with the sole plate. The position of the receptacle is such that the anchoring member 47 extends in a direction substantially parallel with the direction of movement of the right-hand end 85 of member 20 so that when the stem 18 tilts on the diaphragm as a pivot, the anchor member 46 will move in a direction parallel with member 47. The receptacle is secured in place by clamping washer 52 which is 90 flush with the sole plate 10.

As thus constructed and arranged, it will be observed that the fusible metal is secured in the receptacle by the anchoring member 47, while the anchor member 44 has a tendency to carry the metal with it whereby a 95 shearing action is exerted on the fusible metal due to the cooperation of these respectively fixed and movable anchor members. The stem 18 is thus effectively secured until released by the fusing of the metal and creeping of the movable anchor 100 44 and gradual tilting of the stem 18 prevented. Furthermore the fixed anchor member 47 prevents lost motion due to looseness caused by shrinkage of the fusible metal in cooling 105 since while the fusible metal may shrink away from the container in solidifying, it at the same time tightly clamps the fixed anchor member 47 so as to be held in fixed position with relation to the receptacle. It will be 110 observed that the fusible metal is divided into two portions by the anchor member 47 which portions are connected through the apertures 50, and hence the shrinkage of the fusible metal tends to tighten it on the anchor member 47.

For the purpose of preventing the fusible metal from coming in contact with the diaphragm 40, a disc 53 is secured to stem 18 at its lower end just above the anchor member 44. Immediately above the disc 53 and in sliding engagement therewith is a washer 54 which fits snugly in the top of the receptacle 15 below the diaphragm. Upon tilting movement of stem 18, the disc 53 slips freely with relation to the washer 54. The disc and the washer form a tight joint, however, and thus prevent the fusible metal from coming in contact with the diaphragm. The disc and washer are made of a suitable 130

material for which the fusible metal has no affinity, such as mica.

While I have described my invention as embodied in concrete form and as operating in a specific manner in accordance with the provisions of the patent statutes, it should be understood that I do not limit my invention thereto, since various modifications thereof will suggest themselves to those skilled in the art without departing from the spirit of my invention, the scope of which is set forth in the annexed claims.

What I claim as new and desire to secure by Letters Patent of the United States, is:—

1. A temperature cut-out for electric heaters comprising circuit control means for the heater biased to one position, means for holding said circuit control means in another position, a fusible metal for securing said holding means, a container for said fusible metal, and means for securing said fusible metal to prevent looseness in said container irrespective of the amount of shrinkage of the fusible metal in cooling.

2. A temperature cut-out for electric heaters comprising circuit control means for the heater biased to one position, means for holding said circuit control means in another position, a fusible metal for securing said holding means, a container for said fusible metal, and means dependent upon the shrinkage of said fusible metal in cooling for holding said fusible metal rigidly in said container when it is solidified.

3. A temperature cut-out for electric heaters comprising circuit control means for the heater biased to open circuit position, means for holding said circuit control means in closed circuit position, a fusible metal for securing said holding means, a container for said fusible metal, and securing means for the fusible metal comprising a member secured to said container to which said fusible metal clamps itself due to shrinkage in cooling so as to be held immovable with relation to the container.

4. A temperature cut-out for electric heaters comprising circuit control means for the heater biased to open circuit position, means for holding said circuit control means in closed circuit position, a fusible metal for securing said holding means, a container for said fusible metal, and an anchor member secured to said container dividing the fusible metal into two portions and provided with apertures through which the portions are connected whereby the fusible metal shrinks tightly on said anchor member in cooling so as to be rigidly secured thereby in said container.

5. A temperature cut-out for electric heaters comprising circuit control means for the heater biased to open circuit position, a member for holding said circuit control means in closed circuit position, a fusible metal for

securing said holding member, a container for said fusible metal, and a member embedded in said fusible metal extending transversely of and secured to said container, said member being provided with apertures filled with said fusible metal whereby said fusible member shrinks firmly on said member in cooling and is thereby secured in said container.

6. A temperature cut-out for electric heaters comprising circuit control means for the heater biased to one position, a holding member for said circuit control means, a container, a fusible metal in said container, and cooperating anchor members secured respectively to said holding member and said container, said anchor members being embedded in said fusible metal whereby said holding member is secured.

7. A temperature cut-out for electric heaters comprising circuit control means for the heater biased to one position, a member for holding said control means in another position, a container, a fusible metal in said container, an anchor member secured in said container and embedded in said fusible metal, and means on said holding member cooperating with said anchor member so as to apply a shearing force to said fusible metal whereby said holding member is secured.

8. A temperature cut-out for electric heaters comprising circuit control means for the heater biased to one position, a member for holding said control means in another position, a container, a transversely extending member secured in said container and provided with apertures, projections on said holding member adjacent said transversely extending member, and a fusible metal in said container embedding said transversely extending member and said projections so as to secure said holding member.

9. A temperature cut-out for electric heaters comprising circuit control means for the heater biased to one position, a pivoted member for holding said circuit control means in another position, a fusible metal securing said holding member, a container for said fusible metal, a flexible diaphragm closing said container forming a pivot for said holding member, and means for protecting said diaphragm from contact with said fusible metal comprising a member secured in and partially closing said container and a member carried by said holding member forming a tight joint with the first and sliding with relation thereto upon tilting of said holding member.

10. A temperature cut-out for electric heaters comprising circuit control means for the heater biased to one position, a pivoted member for holding said circuit control means in another position, a fusible metal securing said holding member, a container

for said fusible metal, a flexible diaphragm closing said container forming the pivot for said holding member, and means for protecting said diaphragm from contact with said fusible metal comprising a washer secured in said container surrounding said member, and a disc carried by said member cooper-

ating with said washer to form a tight joint and sliding with relation thereto upon movement of said holding member on its pivot. 10

In witness whereof, I have hereunto set my hand this 10th day of January, 1924.

HARRY E. STRUNK.
